(57) **CLAIM**

The ornamental design for a license plate frame, as shown and described.

DESCRIPTION

FIG. 1 is a front view showing our new design for a license plate frame.

FIG. 2 is a left side view of the license plate frame of the present invention, the right side view being the mirror image thereof.

FIG. 3 is a magnified view of a portion of the license plate frame shown in FIG. 1.

FIG. 4 is a back view of the license plate frame of the present invention.

FIG. 5 is a magnified view of a portion of the license plate frame shown in FIG. 4.

FIG. 6 is a top view of the license plate frame of the present invention.

FIG. 7 is a front perspective view of the license plate frame of the present invention; and,

FIG. 8 is a magnified view of a portion of the license plate frame shown in FIG. 7.
